US0D1003270S

(12) **United States Design Patent** (10) **Patent No.:** **US D1,003,270 S**
Chen (45) **Date of Patent:** **** Oct. 31, 2023**

(54) **HEADPHONES**

(71) Applicant: **Libin Chen**, Ganzhou (CN)
(72) Inventor: **Libin Chen**, Ganzhou (CN)
(**) Term: **15 Years**
(21) Appl. No.: **29/813,716**
(22) Filed: **Nov. 1, 2021**
(51) LOC (14) Cl. **14-01**
(52) U.S. Cl. **USPC D14/206**

(58) **Field of Classification Search**

USPC D14/206, 205, 210, 219; D29/112; 2/209; 381/380-381, 370, 374, 346, 309
CPC H04R 25/00; H04R 25/02; H04R 1/1008; H04R 1/10; H04R 1/02; H04R 5/02; H04R 1/1066; H04R 1/1016; H04R 5/033; H04R 5/0335; H04R 1/1091

See application file for complete search history.

FOREIGN PATENT DOCUMENTS

JP D1530020 * 7/2015

Primary Examiner — Paula Allen Greene

(74) Attorney, Agent, or Firm — Sandy Lipkin

(57) **CLAIM**

The ornamental design for headphones, as shown and described.

DESCRIPTION

FIG. 1 is a front view of headphones, showing my new design;

FIG. 2 is a top plan view thereof;

FIG. 3 is a bottom plan view thereof;

FIG. 4 is a rear plan view thereof;

FIG. 5 is a left plan view thereof;

FIG. 6 is a right plan view thereof; and,

FIG. 7 is a perspective view thereof.

1 Claim, 7 Drawing Sheets
